UNITED STATES PATENT OFFICE.

ELI TEETER, OF JERSEY CITY, NEW JERSEY.

OIL-FEEDER FOR INTERNAL-COMBUSTION ENGINES.

1,137,926.

Specification of Letters Patent.

Patented May 4, 1915.

Application filed June 27, 1910. Serial No. 569,124.

To all whom it may concern:

Be it known that I, ELI TEETER, a citizen of the United States, and resident of Jersey City, in the county of Hudson and State of New Jersey, have invented certain new and useful Improvements in Oil-Feeds for Internal-Combustion Engines, of which the following is a specification.

This invention relates to a device for feeding oil under pressure and discharging it in atomized condition into the ignition chamber of an internal combustion engine, and particularly to a device of this kind adapted to feed the heavier distillates of petroleum.

15 The object of the invention is to provide atomizing discharge which may be regulated at will, and to these ends consists in providing a discharge nozzle having its bore or outlet partially closed by a plug which enforces spreading of the fuel and at the same time divides up the spray by compelling it to escape through surface grooves at the periphery of the plug; the discharge end being preferably flared and the entering portion 25 of the plug correspondingly tapered.

In the accompanying drawing, Figure 1 is an axial section of an oil feed device to which my invention is applied; Fig. 2 is an enlarged detail view of the nozzle detached 30 from the oil feeding device and seen from above; Fig. 3 is an axial section of the nozzle with the spraying plug removed; Figs. 4 and 5 are respectively a side and an end view of the spraying plug.

35 Referring to Fig. 1, 1 represents an inlet to which oil is fed under pressure from a suitable external source. 2 is a return by-pass adapted to be closed by needle valve 3, and 4 is a feed duct controlled by a check valve 5 through which the oil is forced when the by-pass 2 is closed. 6^a represents the nozzle to which my present invention relates see Figs. 2 and 3. This nozzle is constructed with a threaded shank 13^a, and 40 screwed into a corresponding socket in the valve body. The plug 9^a Figs. 4 and 5 which is secured in place by its threaded shank 12^a entering the correspondingly

threaded socket in the nozzle 6^a, is provided with a knurled head 10^a which has grooves 50 for the escape of the oil and a central bore 14^b which feeds the symmetrically disposed radial ports 14^a by which the fuel is delivered to the flaring part of the outlet 7^a in the nozzle plug 6^a. The bore 7^a of the plug 55 6^a terminates in a cylindrical portion 7^b which surrounds the substantially cylindrical knurled head 10^a. In this form, the tapered walls constitute a distributing chamber of readily adjustable capacity, while the 60 substantially cylindrical knurled head moving in the cylindrical portion of the bore, maintains the spraying condition with different adjustments of said chamber.

With the form of nozzle and plug described, oil delivered under pressure through the ports 14^b and 14^a is delivered in the form of a flaring and finely-divided spray, or in other words in atomized condition, which adapts it to mingle thoroughly with 70 the contained air or air and other medium in the combustion chamber. By regulating the position of the screw-threaded plug in the bore of the nozzle, the resistance to discharge and, consequently, the degree of 75 atomizing may be regulated at will to a nicety.

I claim:

An oil feed for internal combustion engines comprising a pressure actuated fuel 80 feed and a nozzle supplied thereby; said nozzle being constructed with a bore having a tapered portion and a cylindrical portion beyond the tapered portion, and a plug constructed with a tapered portion conforming 85 substantially to the tapered portion of the bore and with a substantially cylindrical knurled head entering the cylindrical portion of the bore; said plug being adjustable in said bore. 90

The foregoing specification signed at Jersey City this eighteenth day of June, 1910.

ELI TEETER.
